INVENTOR:
Oscar Nygaard,
BY J. M. McCready,
ATTORNEY

UNITED STATES PATENT OFFICE

OSCAR NYGAARD, OF SAUGUS, MASSACHUSETTS

FURNACE WALL

Application filed September 4, 1928. Serial No. 303,653.

This invention relates to furnace walls and is more especially concerned with that type of furnace wall in which tubes are embedded and serve to conduct a fluid medium for carrying heat away from the wall.

Walls of this type are rapidly gaining favor with engineers, particularly in pulverized fuel installations and other furnaces which are operated at high temperatures for long periods of time. In such cases the cooling of the walls in some manner is absolutely necessary to prevent their rapid destruction and the accomplishment of this object by circulating steam or water through pipes embedded in the walls, not only affords a convenient method of controlling the temperature of the wall with a high degree of accuracy, but it is also of advantage in transferring excessive heat from the wall to the boiler, where it adds to the efficiency of the installation.

The present invention aims to improve furnace walls of this general type with a view to simplifying their construction, reducing the first cost, and facilitating the making of repairs.

The nature of the invention will be readily understood from the following description when read in connection with the accompanying drawings, and the novel features will be particularly pointed out in the appended claims.

In the drawings;

Fig. 1 is a front elevation of a small section of a furnace wall constructed in accordance with this invention;

Fig. 2 is a sectional view on the line 2—2, Fig. 3;

Fig. 3 is a sectional view on the line 3—3, Fig. 1;

Fig. 4 is a perspective view of one of the blocks or bricks used in the wall shown in Fig. 1;

Fig. 5 is a horizontal, sectional view of an individual brick or block, showing the manner in which it is held or locked to the tubes;

Fig. 6 is a side elevation of the brick shown in Fig. 5;

Fig. 7 is a view similar to Fig. 5 and shows a modified construction;

Fig. 8 is a side elevation of the brick shown in Fig. 7;

Fig. 9 is a section on the line 9—9, Fig. 2; and

Fig. 10 is a view similar to Figs. 5 and 7 showing a further modification.

Referring first to Figs. 1, 2, and 3, the wall there shown comprises a series of pipes or tubes 2, usually supported in an upright position and in parallel relationship. Associated with these tubes are bricks or blocks 3, arranged in vertical rows, the bricks in each row being located end to end. The construction of the individual bricks is best illustrated in Figs. 3 and 4. It will be observed that each brick is of approximately T shape in horizontal section, and has a face portion to lie in front of and protect the front portions of two adjacent tubes and a rearward extension or tongue 4, which projects between adjacent tubes. Considered from a somewhat different standpoint the bricks may be said to be grooved at their opposite sides to conform to and fit against the surface of the tubes 2 between which they are located.

A short, semi-cylindrical socket 5 is formed in the upper end of each extension or tongue 4, and extends into the brick for only a short distance, this socket opening on to the grooved face of the brick. A similar socket 6 is formed in the lower end of the extension 4 and at the opposite side of this part of the brick. Short pins 7 are located in the sockets 5 and 6, as clearly shown in Fig. 3, and they serve through their engagement with the bricks and the tubes to lock each brick firmly to the two tubes between which it is located. Each brick is thus individually held in its operative position.

The bricks may be made of any suitable highly refractory material such as fire clay, silicon carbide, or the like, the latter material being preferred. The pins also may be made of silicon carbide, or of metal such as iron, steel, or the like.

In building a wall of this construction, the bricks 3 may be inserted from the front or fire face of the wall and the pins 7 then placed in the sockets to lock the bricks in position. After the front section or facing of

- the wall has been completed, then the usual masonry backing, or rear section, may be built immediately behind the tubes. This backing may be of any suitable construction.
- 5 In some cases such a backing will consist of a brick wall, the bricks being laid in the ordinary manner, but being spaced slightly from the tubes, and a packing of asbestos, magnesia, or the like, will be placed in the space between the tubes and the backing. In 10 some cases, also, a metal shell is located at the rearward side of the backing to assist in making the wall absolutely airtight, as shown for example, in my pending application, 15 Serial No. 286,128 filed June 18, 1928.
- When it becomes necessary to make repairs to the wall, it is very desirable to be able to do this work from the fire side of the wall so as to avoid tearing down the rear section of 20 the wall, or that part of it behind the tubes. For this reason I prefer to use key bricks or filler bricks 8, Figs. 1 and 2, at intervals in the vertical rows of bricks 3. It will be seen from an inspection of Fig. 2 that the upper 25 and lower faces of each key brick 8 are inclined so that this brick is held in its operative position by gravity, the abutting end of the faces of the bricks 3 immediately above and below the key brick being correspondingly inclined.
- With this construction it is a very simple matter to replace a broken or cracked brick from the fire side to the wall. Assuming, for example, that it is desired to replace the 35 brick 3, Fig. 1, it is simply necessary to remove the key brick 8, which can readily be done from the fire side of the wall, due to the fact that it is held in the wall simply by gravity. This brick is of such a height that 40 when it is removed access then is afforded to the pins or locking members 7, the lower locking pin being reached through the space formerly occupied by the key brick, while access is readily obtained to the upper pin 45 by allowing the brick 3 to drop. This brick may then be withdrawn at the fire side of the wall, a new brick inserted and locked in position by pins 7 and the key brick 8 may then be replaced in its former position.
- 50 It will thus be observed that the invention provides a wall construction which is exceedingly simple, can be manufactured economically, and in which the making of repairs is greatly facilitated. At the same 55 time the bricks are of such construction that they afford ample protection to the tubes. Abundant bearing surface is provided between the bricks and the tubes to permit a rapid transfer of heat from the latter to 60 the former. This construction also lends itself readily to the necessary modifications to accommodate curves and bends in the tubes as will be obvious, the bricks simply being given a curvature corresponding to that of 65 the tubes.

Under some conditions it may be preferable to provide sockets 5 at both sides of the extension 4 and at both ends thereof. Such a construction is shown in Figs. 5 and 6.

The pins also may be of various cross-sectional forms. Figs. 7 and 8 show a brick 3' of substantially the same form as the brick 3 but held in place by pins 10 which are tapered or wedge shaped in horizontal section, the sockets 11 in which these locking members are located being correspondingly shaped to receive them. Preferably the face of these wedges 10 are curved where they bear against the tubes 2—2 to conform to the shape of the tubes. Since these pins, like 75 the pins 7, engage the tubes at the rear of the plane of the tube centers, they cooperate with the portions of the bricks in front of this plane to lock the bricks securely to the tubes. This construction has a further advantage in affording a broad bearing of the locking members or wedges 10 against the tubes. 85

The area of the tubes which is covered and protected by the bricks will vary somewhat with the practical conditions encountered in individual installations. In some cases, as for example, where the wall is to be used in generating or super heating steam, it may be desirable to expose a considerable 95 portion of the front walls of the tubes to the fire. A brick suitable for this purpose is shown at 3", Fig. 10, the brick otherwise being like that shown in Figs. 7 and 8.

It will also be observed that the extensions 4' of these bricks 3' and 3" are very short so that the rear face of each extension lies approximately in the vertical plane of the rearward sides of the tubes. This is of advantage in saving material and is particularly desirable in those installations where the rear section of the wall is to be placed as close as possible to the tubes. 100

While I have herein shown and described preferred embodiments of my invention, it will be understood that the invention may be embodied in a considerable variety of other forms without departing from the spirit or scope thereof. 110

Having thus described my invention what I claim as new is:

1. In a furnace wall, the combination of a series of substantially parallel tubes, refractory bricks protecting said tubes at the fire-side of the wall and each having a portion extending between said tubes, and wedges fitting against said tubes and engaging the respective bricks and serving by such engagement to hold the bricks to the tubes, the tapering surfaces of said wedges being disposed 120 transversely to the tubes. 125

2. In a furnace wall, the combination of a series of substantially parallel tubes, refractory bricks associated with and protecting said tubes at the fire-side of the wall, said 130

bricks having portions lying between adjacent tubes and fitting against the tubes, the tube engaging faces of the bricks having sockets extending into them from the ends of 5 the bricks, and wedges located in said sockets and serving to hold the bricks to the tubes, said wedges having tapered surfaces disposed transversely to the tubes.

3. In a furnace wall, the combination of a 10 series of substantially parallel tubes, refractory bricks associated with said tubes, said bricks being grooved to fit against the tubes, and pins bearing against the tubes and bricks and serving to lock the bricks to the tubes, the 15 grooved faces of the bricks having sockets open at the end faces of the bricks to receive the pins.

4. In a furnace wall, the combination of a 20 series of substantially parallel tubes, refractory bricks associated with said tubes and each having a part lying between adjacent tubes, and a pin held in said part of each brick adjacent an end face thereof and bearing against one of said tubes and serving to hold 25 the brick to the tube, said pin extending approximately parallel to the tube.

5. In a furnace wall, the combination of a 30 series of substantially parallel tubes, refractory bricks associated with said tubes, each of said bricks having a part protecting the front of a tube and a portion extending between adjacent tubes, said portion being provided adjacent an end face thereof with a socket close beside and approximately parallel to one of the tubes, and a locking pin in said socket bearing against said tube and holding the brick to the tube.

6. In a furnace wall, the combination of a 40 series of substantially parallel tubes, refractory bricks associated with said tubes, each of said bricks having a face portion lying in front of two adjacent tubes and a projection extending rearwardly therefrom into the space between said tubes, said projection having sockets adjacent end faces of the 45 bricks and close beside and approximately parallel to said tubes, and locking pins in said sockets bearing against said tubes and holding the bricks to the tubes.

50 7. In a furnace wall, the combination of a series of substantially parallel tubes, refractory bricks associated with said tubes, and wedges having their tapered surfaces disposed transversely to said tubes, said wedges being shaped to fit against the tubes and operative through engagement with both the tubes and bricks to lock the bricks to the tubes.

8. In a furnace wall, the combination of a 60 series of substantially parallel tubes, refractory bricks bearing against said tubes, each of said bricks having a part protecting the front of a tube and a portion extending between adjacent tubes, said portion being provided with a socket adjacent an end face 65 thereof and close beside one of the tubes at the

rearward side of the tube, and a pin in said socket bearing against and lying parallel to said tube and holding said brick to the tube.

9. In a furnace wall, the combination of a 70 series of substantially parallel tubes, refractory bricks bearing against said tubes, each of said bricks having a face portion lying in front of two adjacent tubes and a projection extending rearwardly therefrom into the space between said tubes, said projection having sockets extending inwardly from the end faces thereof and located close beside said tubes, and locking pins in said sockets bearing against the rearward sides of said tubes and holding the brick to the tubes. 80

10. In a furnace wall, the combination of a 85 series of upwardly extending parallel tubes, bricks arranged in rows and having face portions lying in front of said tubes and protecting the tubes at the fire side of the wall and projections extending rearwardly from said face portions and located between adjacent tubes, said bricks being constructed to be placed in or removed from the wall at the fire side thereof, key bricks located at intervals 90 in said rows and held in their operative positions in the wall by gravity but being removable from the wall at the fire side thereof, and means for normally locking said bricks other than the key bricks against removal, said 95 means being located adjacent an end face of each of said bricks whereby access thereto is afforded by the removal of the key bricks.

11. In a furnace wall, the combination of a 100 series of upwardly extending parallel tubes, bricks arranged in rows and having face portions lying in front of said tubes and protecting the tubes at the fire side of the wall and projections extending rearwardly from said face portions and located between adjacent 105 tubes, said bricks being constructed to be placed in or removed from the wall at the fire side thereof, means adjacent an end face of each of said bricks cooperating with said projections to lock the bricks to the tubes, and key bricks located at intervals in said rows and removable from the wall at the fire side thereof, said key bricks being of such dimensions that their removal affords access to the locking means for bricks next adjacent to 110 them.

12. A brick for furnace wall construction having a groove in one side thereof to fit partly around a tube, and a socket in one end of said brick opening into the grooved face 120 thereof and extending for a short distance only into the brick.

OSCAR NYGAARD.
